UNITED STATES PATENT OFFICE.

FRIEDRICH OTTO RUEHLE AND ALBERT GUSTAV SCHMIDT, OF NEWARK, NEW JERSEY, ASSIGNORS TO THE AMERICAN ART STOVE AND MANTEL COMPANY, OF SAME PLACE.

STOVE.

SPECIFICATION forming part of Letters Patent No. 484,113, dated October 11, 1892.

Application filed April 4, 1892, Serial No. 427,595. (No model.)

To all whom it may concern:

Be it known that we, FRIEDRICH OTTO RUEHLE and ALBERT GUSTAV SCHMIDT, both subjects of the Emperor of Germany, residing in Newark, county of Essex, and State of New Jersey, have invented certain new and useful Improvements in Stoves; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide a kitchen-stove of which tiles form an important part in the construction thereof, simple and durable, of great efficiency, and neat in appearance.

20 The invention consists in the improved kitchen-stove, the arrangements of the fireplaces and smoke consumers, and in the combination and arrangements of the various parts thereof, substantially as will be herein- 25 after more fully described, and finally embodied in the clauses of the claim.

Referring to the accompanying drawings, in which like letters of reference indicate corresponding parts in each of the several views,

30 Figure 1 is a perspective view of the improved kitchen-stove. Fig. 2 is a sectional view on line x y , Fig. 1; and Fig. 2^a is a perspective view of one of the grates.

In said drawings, a represents the stove 35 with mantel b and top c . The stove, as well as the mantel, is built of tiles and surrounds the foundation a' . In said stove are arranged the ovens d and surrounding chamber d' , and underneath the fireplace f , with grate f' . At 40 the other end of the stove is arranged another fireplace g , (with grate g'), and between the two fireplaces the dish-oven e , hot-water tank h , and damper h' . Between the fireplace g and the dish-oven e and secured to the top c is ar- 45 ranged an iron plate o , projecting downwardly into a recess a^2 , which acts as a smoke-consumer, being heated by the flames from said fireplace. Each grate is provided with upwardly-extending flanges g^2 , having slots g^3 , (preferably 50 horizontal,) which perforated flanges partially

serve as smoke-consumers. Between the fireplace g and the side wall of the stove a is arranged a channel l' , connected through an inlet l with the outer atmosphere. Said inlet l is provided with a suitable ventilator. (Not 55 shown in the drawings.) Between the oven d (or, better, between the wall of the surrounding chamber d') and the outer walls of the stove a is arranged a chamber m' , provided with a ventilator m . The hot-water tank h is 60 situated between the dish-oven e and the ovens d and is connected through pipes K and i with the cold and warm water supply, respectively. Both pipes are so arranged that the larger portion of them is inclosed in 65 the stove or its mantel, whereby the said pipes are always kept warm. The damper h' is arranged so that it may, by turning the handle h^2 , shut off the communication between the fireplaces f and g , thus allowing each of the 70 said fireplaces to be used independently of the other.

In operation, when a fire is made in the grate of fireplace g the flames and smoke will pass over and through the perforated flanges g^2 of the grate, thus heating said flanges, whereby part of the smoke will be consumed. The remainder of the smoke is compelled to pass over and under the plate o , which also becomes heated, and thereby acts as an additional smoke-consumer. The heat and such portion of the smoke that remains unconsumed pass over the top of the dish-oven e and over and around the hot-water tank h and from there into the chamber d' , surround- 85 ing the ovens d , and finally into the chimney.

If it is desired to use only the ovens d , the damper h' is thrown over so as to rest against the wall of the chamber d' , as shown in dotted lines in Fig. 2, and the fire is built in the 90 fireplace f .

Should the tiled surface of the stove become too warm, the ventilator at l is opened, thus allowing the cold air to pass through said ventilator into the chamber l' , from there over the fireplace g , and along over the dish-oven and water-tank into the outer chamber or channel m' . As will be manifest, the said air (in its described passage) when leaving the ventilator m has become heated. A con- 95 roo

nection can easily be attached to said venti-
lator *m* and piped off to other rooms in any
desired manner, thus combining with the or-
dinary kitchen-stove valuable means for heat-
ing the various rooms in other parts of the
house.

Having thus described our invention, what
we claim as new, and desire to secure by Let-
ters Patent, is—

- 10 1. A kitchen-stove combining therein two
fireplaces, a grate arranged in each of said
fireplaces and provided with upwardly-ex-
tending perforated flanges, and a damper be-
tween said fireplaces and adapted to make
15 each of said fireplaces independent of the
other, substantially as described and set forth.
- 20 2. A kitchen-stove having two fireplaces
and provided with a vertical plate adjacent
to one of said fireplaces, depending from the
top of the stove and terminating in about the
plane of the grate in said fireplace.
- 25 3. A kitchen-stove combining therein two
fireplaces, a grate arranged in each of said
fireplaces and provided with upwardly-ex-
tending perforated flanges, a hot-water tank

arranged between said fireplaces, a damper so
arranged as to make each of said fireplaces
independent of the other, and a downwardly-
extending iron plate serving as a smoke-con-
sumer, all said parts being arranged to oper-
ate substantially as described and set forth. 30

4. In a kitchen-stove, the combination, with
the ovens and fireplaces, of grates arranged
in said fireplaces and provided with upwardly-
extending perforated flanges, cold-air 35
chambers *l'* and *m'*, arranged in said stove
and connected with the outer atmosphere
through ventilators *l* and *m*, and a damper ar-
ranged between said fireplaces and chambers,
all said parts being arranged substantially as 40
described, and for the purposes set forth.

In testimony that we claim the foregoing
we have hereunto set our hands this 26th day
of March, 1892.

FRIEDRICH OTTO RUEHLE.
ALBERT GUSTAV SCHMIDT.
